UNITED STATES PATENT OFFICE

106,317

DESIGN FOR A SERVICE BAR

James Mont, New York, N. Y.

Application August 25, 1937, Serial No. 71,309

Term of patent 3½ years

To all whom it may concern:

Be it known that I, James Mont, a citizen of Turkey, residing in the city of New York, county of New York, and State of New York, have invented a new, original, and ornamental Design for a Service Bar, of which the following is a specification, reference being had to the accompanying drawing, forming part thereof.

The drawing is a perspective view of a service bar, showing my new design.

The opposite end is identical with the end shown.

The rear of the bar is conventional.

I claim:

The ornamental design for a service bar substantially as shown and described.

JAMES MONT.
